UNITED STATES PATENT OFFICE.

HARRY AUSTIN KNOX, OF SPRINGFIELD, MASSACHUSETTS.

INTERNAL-COMBUSTION ENGINE.

1,075,580.

Specification of Letters Patent.

Patented Oct. 14, 1913.

Application filed July 16, 1912. Serial No. 709,638.

To all whom it may concern:

Be it known that I, HARRY A. KNOX, a citizen of the United States of America, residing at Springfield, in the county of 5 Hampden and State of Massachusetts, have invented new and useful Improvements in Internal-Combustion Engines, of which the following is a specification.

This invention relates to improvements in 10 internal combustion engines of the type in which a sliding sleeve is used to control the inlet and exhaust ports.

The primary object of the invention is to provide an improved form of positively acting slide valves to control the outgoing exhaust gases from the combustion chamber and to control the incoming charge to the combustion chamber.

In carrying out the objects of the invention, the usual stationary cylinder is employed which is bolted or otherwise secured to the crank case, and a movable valve-sleeve is located in the cylinder and has a sliding bearing on the inner surface of the cylinder 25 wall. The usual piston is located within the movable sleeve and a cylinder head which is attached to and closes the upper end of the cylinder provides a convenient means for gaining access to the interior of the cylinder 30 for cleaning or repairs. This head is so formed that a part of the same projects into the cylinder so as to make or leave an annular space between it and the inside wall of the cylinder and into which space the upper- 35 most end of the sleeve slides or moves, said sleeve having a bearing on said downwardly projecting portion of the cylinder-head.

Located in parallel relation to the axis of the cylinder, and in one side thereof, is 40 formed a groove or channel which extends the entire length of the bore of the cylinder. In this channel is located a slide valve which moves freely up and down. This valve is concavo-coavex in cross section, the concave 45 part of which bears against the outer convex surface of the valve sleeve, said bearing surfaces having the same radius.

Prior to my invention, internal combustion engines have been constructed with slide 50 valves in which two sliding sleeves are employed; also engines having a single sliding sleeve,—the sleeve having an oscillating as well as a reciprocating motion imparted thereto. I am also aware that engines have 55 been built with a single sliding sleeve combined with a rotary valve at the side; also I

am aware that engines have been built with one sliding sleeve and a reciprocating round plug valve in the side of the cylinder.

In engines of the two sleeve type, the side 60 thrust of the piston at two points in the engine cycle is directly transmitted against both the sleeves with the result that about twice as much friction is developed as with the single sleeve type of engine, resulting in 65 a large loss of efficiency. In engines which employ a single sleeve and to which a reciprocating and oscillating motion is imparted, it is necessary to give to the sleeve a longer 70 stroke with a result that loss by friction is enhanced in providing sufficient exhaust and inlet openings. In this type of engines a very complicated means of operation is necessarily required.

In many internal combustion engines having 75 a single sleeve and a rotating valve or round plug and a slide valve at the side, there is, after each exhaust stroke, a large 80 volume of the burned gas caught in the exhaust port of the cylinder, and also in the port of the rotating or sliding valve with the result that when a fresh charge is drawn 85 into the cylinder these exhaust or burned gases are sucked back into the combustion chamber on the in-take stroke, thus diluting 90 the incoming charge and again reducing the efficiency of the engine. In the present invention these various objections have been overcome by the use of a single sliding sleeve and a single sliding valve, in which the movable sleeve is provided with only a single 95 port thereby reducing the loss by leakage to a minimum; and as the inlet charge is immediately drawn in through this port after the hot exhaust gases have been expelled 100 therefrom, the new incoming gases have a tendency to cool the port edges and to keep them free from the carbon deposits.

My invention will be fully described by reference to the accompanying drawings 105 which form a part of the specification and in which,—

Figure 1 is a vertical, longitudinal section through the axis of the cylinder showing the relation of the single sleeve and 110 sliding valve; also illustrating the driving connection between the engine shaft and the crank or eccentric shaft, and the connections between the piston, sleeve, sliding valve, and the eccentric shaft. Fig. 2 is a transverse 115 sectional view on the line 2—2 of Fig. 1 showing the relation of the sliding sleeve

and slide valve at the point in the cycle of operations at the beginning of the working or power stroke, with the exhaust port closed. Fig. 3 is a detailed view on the line 3-3 of Fig. 1 showing the opening in the slide valve through which the inlet or incoming charge passes and its relation to the sliding sleeve; also showing the single opening in the sleeve. Fig. 4 is a detailed view showing the relation of the moving parts at the beginning of the opening of the exhaust port, and particularly, the position of the piston when in its lowermost position and about to return on its upward or exhaust stroke. Fig. 5 shows the position of the movable parts at the instant the exhaust port closes, and the inlet port is about to open. Fig. 6 shows the position of the movable parts when the inlet has just closed and the piston is about to make its compression stroke.

Referring to the drawings in detail, *a* designates the cylinder of the engine and *b* the crank-case which is attached to the lower end of the cylinder in the usual way. In this crank-case is located the crank-shaft *c* and the cam or eccentric shaft *d*.

e designates a chain drive between the two shafts, and, as usual, the rate of rotation is made two to one, that is to say, two revolutions of the crank-shaft to one of the cam or eccentric shaft.

f designates the cylinder head that is secured to, and closes the upper end of, the cylinder *a* and which projects downward into the bore of the engine cylinder as shown. This cylinder head is formed with its depending portion *g* of smaller diameter than the bore of the cylinder to provide the space *h* between the depending portion *g* and the internal wall of the cylinder. This space is designed to receive the upper end *i* of the movable sleeve *j* which has a bearing on said portion *g* of the head. The sleeve is operated by means of the connecting rod *k*, its upper end being connected to the lug *m* on the lower end of the sleeve *j*, and its lower connection being made with the cam or eccentric shaft *d*.

o designates a slide valve which is mounted in a channel or groove *p* that is drilled or formed in parallel relation to the axis of the cylinder *a* and of the same length. This slide valve is operable from the cam-shaft *d* by means of a connecting rod *q* its upper end being attached to a lug *p* on the lower end of the slide valve *o* and its lower end connected to the cam-shaft *d*. The slide valve *o* is provided with two ports, an inlet port *r* and an exhaust port *t*. The sleeve *j*, is provided with a single opening *v*, in the upper portion thereof, which at a certain point in the cycle of operation, will register with the inlet port *r* and at another point with the exhaust port *t*. When the open-

ing *v* registers with the inlet port *r*, communication is established between the interior of the cylinder and the port *a'*, which allows the charge from the carburetor to pass through the pipe *s* to the cylinder. When the opening *v* registers with the port *t* in the slide valve *o*, communication is established between the interior of the cylinder and the exhaust port *a''*, which allows the burned gases to escape through the exhaust pipe *u*. The usual water jacket is shown at *w*, and the pipe connections leading thereto at *x* and *y*.

The manner of connecting the rods *k* and *g* and the sleeve *j* and slide valve *o* is such that they are nearly ninety degrees apart, as clearly shown in the figures, and have substantially the same length of stroke, the difference in the length of stroke being indicated by the circles shown at 3, Fig. 1. The usual piston and packing rings are shown at 4 and 5. The direction of rotation of the engine shaft is shown by the arrow *6*, and therefore during the power or explosive stroke, the thrust action of the connecting rod *7* between the piston *7* and the shaft *c* is directed away from the slide valve *o* thus permitting this valve to slide more freely with practically no loss from friction. This is an important feature, as in engines of the two sleeve type the thrust of the connecting rod that is transmitted to the inner sleeve and from that to the outer sleeve results in loss of efficiency in operation.

Referring now to the operations of the sleeve *j*, slide valve *o*, and the piston of the engine: In the position of the parts shown in Fig. 1, the piston is just starting on its power stroke with both the inlet and exhaust ports closed. Fig. 4 shows the position of the parts at the end of the power stroke and the beginning of the registration of the port *v* with the exhaust port *t* in the slide valve and the port *a''*,—the sleeve *j* and the slide valve *o* both traveling in the same direction, but the sleeve traveling faster than the slide valve. The position of the parts as shown in Fig. 5 is after the piston has reached the end of its exhaust stroke and the burned gases have been expelled and the port *v* closed from communication with the port *t*. This is also the position of the parts at the beginning of the suction or intake stroke as the continued movement of the slide valve downward will bring the ports *r* and *v* into registration and permit a fresh charge to enter the combustion chamber.

The position of the parts shown in Fig. 6 is that at the end of the suction stroke after the closure of the inlet ports *v* and *r* has taken place and at the beginning of the compression stroke, the last step showing the position of the parts as in Fig. 1 which is at the beginning of the explosive or

power stroke with the ports closed. At the end of the exhaust stroke of the piston, the exhaust passage in the slide valve moves down and out of register with the port in the sleeve. The inlet passage in the slide valve comes into register with the port in the sleeve immediately after the exhaust passage is closed and during the suction stroke of the piston. This allows the incoming 10 charge to pass through the inlet port of the cylinder, through the inlet passage of the slide valve, through the port in the sleeve into the combustion chamber.

What I claim, is:-

15 In an internal combustion engine, the combination of a cylinder having a channel or groove formed in the bore of the cylinder and extending the entire length of said bore, a sleeve in movable contact with the inside 20 surface of said cylinder, a piston in movable contact with the inside of said sleeve, a valve member movable in said channel in

contact with a part of the external surface of said sleeve, a port in the sleeve through which the inlet and exhaust gases pass, an 25 exhaust passage in the valve member adapted to form a communication with the port in the sleeve and with the exhaust port in the cylinder during the exhaust stroke of the piston, an inlet port in the valve member 30 adapted to form a communication with the port in the sleeve and with the inlet port in the cylinder during the in-take or suction stroke of the piston and, connecting rods directly connecting the lower ends of 35 said sleeve and valve member with cranks on the eccentric shaft, means for imparting motion to the sleeve, eccentric shaft, and the slide valve.
